GARMENT PRESSING MACHINE

William Strobridge, Syracuse, N. Y., assignor to
United States Hoffman Machinery Corpora-
tion, New York, N. Y., a corporation of Dela-
ware

Application April 17, 1936, Serial No. 75,007

13 Claims.

(Cl. 38—36)

This invention pertains to garment presses, and relates more particularly to that type wherein one of the pressing elements, as for instance the head, is moved into pressing relation with the cooperative element, the buck, through suitable pressure applying mechanism. The structure to which the present invention is directly applicable is of that class wherein the head is carried by an arm or lever and the pressure applying mechanism which is associated therewith is of the dual toggle or linkage type.

The main object of the invention is to provide a simple and efficient automatic lock for the toggle mechanism, one which may be readily and easily released by the operator through manipulation of a hand lever, or a foot lever, as the case may be.

A further object is to so construct the mechanism that the elements of the lock will always be in contact, thereby precluding the noise of contact or the hammering of one part upon another.

A still further object is to provide a bumper included in the toggle lever system which has the function of cushioning the final locking of the toggle system. Such arrangement ensures a gradual and "jarless" stop, which, in addition to relieving the operator's foot from the common jarring action, also eliminates the "thump" which inheres in the usual toggle actuated press.

A press embodying the invention is disclosed in the annexed drawing, wherein:

Figure 1 is a side elevation of the press, with a portion of the side frame or base broken away, and wherein the press head and allied parts are shown in dotted lines when the press is opened; and

Fig. 2, a vertical sectional view on the line II—II of Fig. 1.

Insofar as the framing of the press is concerned, it is of the usual and ordinary type, comprising a base 10 surmounted by the frame proper, comprising side elements or plates 11 and 12 and an upwardly extending arm 13 at the rear of the frame. The buck, denoted by 14, is secured upon the buck support 15. To the upper end of the arm 13 is pivoted the head carrying lever 16, carrying at its forward end the head 17 and at its rear having a counterweight 18. The pivotal point of the main head carrying lever is denoted by 19.

The means for closing the press may be said to comprise a primary toggle and a secondary toggle. The forward element of the primary toggle, denoted by 21, is preferably formed as a single casting and is fulcrumed or pivoted upon a shaft

22 supported by the side walls 11 and 12, as is usual. The rear element or link of the primary toggle is denoted generally by 23 and has its forward end bifurcated to receive the rear end of the member 21, and these members are pivotally connected by a shaft or elongated pin 24 held against longitudinal movement with reference to the links by cotter pins 25 and 26. (See Fig. 2).

The shaft 24, as will be best seen upon reference to Fig. 2, extends outwardly to one side or 10 toward the wall 11 of the press frame, and has mounted thereon a roller 27 held in place by any suitable means, as by a cap screw 28. The purpose of this roller will presently appear.

Link 23 at its rear end is also bifurcated and 15 engages a pivot pin 29 which extends through the lower link 31 of a secondary or rear toggle, the upper link of which is indicated by 32. The pivotal connection between the upper and the lower links is denoted by 33, and the upper end of the 20 link 32 is pivotally connected to the short arm of a bell crank lever 34 pivotally mounted as at 35 to the rear portion of the head carrying lever 16.

To the upper end of the upwardly extending arm of the elbow lever 34 there is pivotally connected an internally threaded sleeve 30 into which is screwed a rod 36, the rod extending forwardly and having mounted thereon a hand wheel 37 which, working in conjunction with a fixed abutment 38 carried by the head lever 16, permits of 30 angular adjustment of the bell crank 34 and, consequently, varies the effective point of connection of the secondary toggle with the head carrying lever. This adjustment of the point of connection of the rear toggle is the same as that set forth in 35 Letters Patent No. 1,939,149, dated December 12, 1933.

Normally, the press head will be held in its elevated position, this through the action of the usual spring denoted by 39 connected at its upper 40 end to the upper link 32 of the rear toggle as at 41, and at its lower end to a threaded rod 42 which passes freely through the shaft 22, a nut 43 being mounted upon the lower end of the rod. By turning the nut on or off, the tension of the 45 spring can be varied and the head 17 brought into proper balanced relation.

The rear link 23, as will be best seen upon reference to Fig. 1, is substantially inverted T-shape in form, and the upwardly extending arm 50 thereof, denoted by 44, forms a support for a bumper designed to coact with a pad 45 formed upon the upper end of the lower element 31 of the secondary toggle mechanism, or at a point adjacent the pivotal point 33. The upper end of 55

the arm 44 is tapped and a threaded rod 46 is mounted therein, that end of the rod which extends toward the pad 45 carrying a cup 47 in which is mounted a rubber bumper 48. In operation, the bumper comes into contact with the pad 45, as will be hereinafter set forth in detail.

The roller 27, heretofore referred to, forms one element of the press locking or latching mechanism, the other element of which is a pawl or latch designated generally by the numeral 49 and pivoted on a fixed stud or bolt 50 which is carried on the side wall 11 of the machine frame. The element 49 has a latching shoulder 51 which is normal to a radial line drawn through the axis 50 and beyond the shoulder 51 the element 49 has a tail-like extension 52 which is at least coextensive with the arcuate path of the roller 27 as it swings with the lever 21 about the pivot 22. The extension 52 is so positioned that it engages the roller 27 as the lever 21 swings, and engagement between these two parts is insured through the hand release lever and its associated spring, as will be hereinafter more fully explained.

In the particular embodiment shown in Fig. 1, with the latch in disengaged position, as shown in dotted lines, the surface of the extension 51 which contacts the roller 27 is a circular arc concentric with the pivot 22. This exact arrangement is not strictly necessary but when adopted the latch does not move as the lever 21 swings from the dotted line position of Fig. 1 toward the full line position of Fig. 1 until just before the full line position is reached. The parts are so arranged that the primary toggle 21, 23, never reaches full straightened position, but in the final position closely approaches this. Just as the toggle reaches the final position above defined, the roller 27 has risen far enough so that the latching surface 51 can and does enter beneath the roller, thus locking the press in closed position. The important thing in the arrangement described is that the roller holds the latch in disengaged position throughout the swinging movement of the lever 21 and frees the latch to move to engaged position just as the press reaches the limit of its closing movement. It follows that the latch is never struck by the roller and silent operation results.

The member 49 is also provided at its upper portion with a laterally extending arm 53, the outer end of which is bifurcated (see Fig. 2) and is designed to receive the upper end of a threaded rod 54 which passes freely therethrough. A nut 55 mounted upon the rod bears against the rounded under face of the arm and is designed to rock the arm through the depression of the outer end of a foot lever 56, fulcrumed at 57 and normally held in the position shown in Fig. 1 by a spring 58. The rod 54 is attached to the inner end of the lever 56 through a suitable member 59. Since the nut 55 affords only one way thrust engagement with the arm 53, the latch can be released without entailing motion of the pedal 56.

As will be readily seen, when the operator steps upon the outer end of the lever 56, it will rock the latch 49 and swing it out of engagement with the roller 27, this assuming that the parts are in the position shown in full lines in Fig. 1. In order to release the latch through hand manipulation, there is secured to the arm 53 a rod 61 connected at its upper end to a pivoted bell crank 62 which, in turn, has its other end connected to a second rod 63, said latter rod extending forwardly over the head 17 where it is attached to a bell crank lever 64 carrying a pad

or handle 65. A spring 66 underlies the forward portion of the bell crank lever 64 and acts to rock the parts so that the extension 52 of the latch is normally held in contact with the roller throughout the travel of the latter.

Upon rocking of the lever 64 by depressing the pad 65 which is carried thereby, the operator through finger manipulation and the connections above described, may rock the latch 49 and withdraw it from locking engagement with the roller 27, and release the parts in the same manner as if the foot pedal 56 were depressed. By having the upper end of the rod 54 pass freely through the bifurcated end of the arm 53, there is no work imposed upon the operator in the finger release, except that of disengaging the latch from the roller. In other words, the resistance of the spring 58 underlying the foot lever 56 does not have to be overcome. The locking portion of the latch, it will be noted, is located at the pivotal joint of the links of the primary toggle, since at this point the amount of pressure required to release the latch is the minimum.

Obviously the latch may be disengaged either by the finger operated pad 65 or by the foot operated pedal 56 and if only a single control is desired either may be omitted. The fact that the finger operated release does not entail motion of the foot actuated release is considered a desirable feature.

A study of the relative movements of the points in the lever system will indicate that the roller 27 in moving from unlocked to locked position of the system, travels materially faster than does the pivotal connection 33 of the secondary toggle, that is to say, as the toggle moves toward straightened position.

As will be appreciated upon examination of the drawing, the link 23 of the primary toggle is relatively short and it follows, therefore, that the bumper 48, which occupies a position intermediate the shaft 24 and the pivotal connection 33, will also travel at a greater speed than the point 33. Thus, a gradual or pre-stopping occurs between the rubber bumper 48 and the pad 45 upon the toggle member 31, cushioning the final locking action of the lever system and bringing it to what may be termed a jarless stop.

It will be observed that the engagement of the bumper 48 with the pad 45 limits the press closing movement of the linkage and that the buffering reaction is between the relatively fast moving element 23 of the primary toggle and a pad or boss located adjacent the hinge of the slow moving secondary toggle. The buffer and pad 55 at the moment of engagement move in approximately coincident paths, and at the limit of movement with the bumper in engagement with the pad and under compression the latch engages. It follows that there is no recoil and that the shock of arresting the linkage is largely absorbed within the linkage itself. To whatever extent it is not so absorbed it develops a closing tendency of the press head against the goods imposed upon the buck, a reaction which the press is designed to withstand and absorb. Consequently the press closes and locks silently and positively. It will be observed that the bumper 48 is adjusted at 46 with reference to the roller 27 which serves as the keeper for the latch. By adjusting the bumper the point of arrest of the linkage can be determined so that it substantially coincides with the point of engagement of the latch.

When the latch is released, the head of the 75

press 17 will tend to swing open and during such opening movement from full line to dotted line position (Fig. 1), the roller 27 will follow the cam surface formed upon the tail-like extension 52 of the latch.

It will be understood that when the press is closed and the parts brought to the full line position as in Fig. 1, the latch will hold them closed until the latter is released. In other words, the 10 primary toggle will have been brought to a pressure exerting position just short of being straightened and cannot break. The pivotal connection or pin 24 of the toggle is, therefore, held against downward movement until such 15 time as the latch 49 may be swung clockwise to carry the locking face 51 from beneath the roller; whereupon, the spring 39 will be free to draw the head and its related parts to the dotted line position.

20 What is claimed is:

1. The combination of a press, comprising relatively movable pressing elements; actuating means therefor comprising a secondary toggle arranged to develop the pressing stress between said members as it approaches straight position, and a faster-moving primary toggle connected to shift the secondary toggle toward straight position as the primary toggle approaches straight position; and buffering means interposed between components of the respective toggles, and arranged to become effective as the two toggles approach straight positions, whereby the buffering reaction occurs between moving elements of the two toggles, and the resulting shock is substantially absorbed therein.

2. The combination of a press, comprising relatively movable pressing elements; actuating means therefor comprising a secondary toggle arranged to develop the pressing stress between said members as it approaches straight position, and a faster-moving primary toggle connected to shift the secondary toggle toward straight position as the primary toggle approaches straight position; and buffering means interposed between components of the respective toggles, which components, as the two toggles approach straight positions, move in substantially the same direction at unequal speeds, the parts being so arranged that a fast moving component of the primary toggle reacts through said buffer against a slower moving component of the secondary toggle to develop a press closing impulse upon the secondary toggle.

3. The combination of a press, comprising relatively movable pressing elements; actuating means therefor comprising a secondary toggle arranged to develop the pressing stress between said members as it approaches straight position, and a faster-moving primary toggle connected to shift the secondary toggle toward straight position as the primary toggle approaches straight position; a resilient buffer arranged to be compressed by relative motion of components of the respective toggles as the two toggles approach straight positions, and to arrest motion of the toggles slightly before such positions are reached; and a latch for locking the primary toggle substantially at the point of arrest.

4. The combination defined in claim 3 in which the latch comprises a shiftable pawl having an arcuate tail, and a coacting roller, the roller serving to guide the tail of the pawl throughout the motion of the toggle to the point 75 of arrest, where it clears the tail and permits it

to engage behind the roller which then serves as a keeper.

5. The combination of a press, comprising relatively movable pressing elements; actuating means therefor comprising a secondary toggle arranged to develop the pressing stress between said members as it approaches straight position, and a faster-moving primary toggle connected to shift the secondary toggle toward straight position as the primary toggle approaches straight 10 position; a resilient buffer arranged to be compressed by relative motion of components of the respective toggles as the two toggles approach straight positions, and to arrest motion of the toggles slightly before such positions are 15 reached; a latch for locking the primary toggle substantially at the point of arrest; and means for effecting a relative adjustment between a component of the buffer and a component of the latch whereby said point of arrest and the point 20 of engagement of the latch may be coordinated.

6. The combination of a press, comprising relatively movable pressing elements; actuating means therefor comprising a secondary toggle arranged to develop the pressing stress between 25 said members as it approaches straight position, and a faster-moving primary toggle connected to shift the secondary toggle toward straight position as the primary toggle approaches straight position; a resilient buffer arranged to be compressed by relative motion of components of the respective toggles as the two toggles approach straight positions, and to arrest motion of the toggles slightly before such positions are reached; a latch for locking the primary toggle substantially at the point of arrest; means for effecting a relative adjustment between a component of the bumper and a component of the latch whereby said point of arrest and the point of engagement of the latch may be coordinated; and independent adjusting means for varying the pressing 30 force developed between the pressing elements by the secondary toggle at said point of arrest.

7. In a pressing machine, the combination of a 45 pair of pressing members, one movable relatively to the other; means embodying at least one toggle for moving the movable element into pressing relation with the other; a roller carried by a swinging element of said toggle and adapted to 50 serve as a keeper for a latch; a latch pivoted to a fixed portion of the frame, said latch having a shouldered portion adapted to engage behind said roller when the latch is engaged, said latch having an extension or tail-piece with which the 55 roller contacts to determine the release position of the latch when the toggle is broken and is moved toward or from press closing or opening position; an arm extending laterally from the upper portion of the latch; and means associated with said arm for withdrawing the shouldered portion of the latch from the roller.

8. In a pressing machine, the combination of 65 relatively movable pressing elements; power applying means for the movable element, comprising a primary toggle and a secondary toggle, the former being pivotally connected to the latter at a point below the pivotal connection of the links of the same; a latch for maintaining the primary toggle in its power applying position; and a bumper carried by said primary toggle and contacting the secondary toggle at a point above the pivotal connection of the links of said secondary toggle.

9. In a pressing machine, the combination of relatively movable pressing elements; means for actuating the movable element, comprising a primary toggle and a secondary toggle and means for actuating the primary toggle; an arm extending upwardly from the link of the primary toggle, which link is pivotally connected to the rear toggle at a point below the pivotal connection of the links of the secondary toggle; and a bumper carried by the upwardly extending arm and adapted as the toggles assume press closing position to contact said secondary toggle and arrest any jarring action which might otherwise inhere.

10. A structure as set forth in claim 9, wherein the bumper is adjustable with reference to the arm by which it is carried, toward and from the secondary toggle.

11. In a pressing machine, the combination of relatively movable pressing elements; a pivoted lever by which the movable pressing element is carried; a toggle mechanism for swinging the lever, comprising a primary and a secondary toggle; and a bumper carried by one of said toggles

and adapted as the parts come to final pressing position, to contact the other toggle.

12. In a pressing machine, the combination of relatively movable pressing elements; means for moving one of said elements into contact with the other, said means comprising two interrelated toggles and means for actuating the same; and a bumper mounted upon and movable with one of said toggles and contacting the other toggle when the parts approach the final pressing position.

13. In a pressing machine, the combination of relatively movable pressing elements; means for moving one of said elements into contact with the other, said means comprising a primary toggle and a secondary toggle and means for actuating the primary toggle, said primary toggle embodying a rear link relatively short as compared to the forward link thereof, and said short link being connected to the secondary toggle at a point below the pivotal connection of the links thereof; and a bumper carried by said short link of the primary toggle.

WILLIAM STROBRIDGE.
